UNITED STATES PATENT OFFICE.

ISAAC A. STEIN, OF GALVESTON, TEXAS.

BEVERAGE-DISPENSING APPARATUS.

Application filed September 8, 1923. Serial No. 661,567.

To all whom it may concern:

Be it known that I, ISAAC A. STEIN, a citizen of the United States, and a resident of Galveston, Galveston County, Texas, have 5 invented a certain new and useful Improvement in Beverage-Dispensing Apparatus, of which the following is a full, clear, and exact description, such as will enable others skilled in the art to which it appertains to 10 make and use the same.

My invention relates to an apparatus for refrigeration and dispensing of carbonated beverages. The object of the invention is to provide an efficient apparatus for dispensing 15 prepared beverages by the pressure of the carbonated material, such instrument being in a particularly efficient and compact form. It is desired that the construction of the refrigerating compartment be such that the 20 device may be connected and disconnected and new parts substituted without disassembling the device.

Another object is to provide a supporting 25 means for the pipes connected with the refrigerating apparatus, and to support said pipes in a particularly efficient manner.

Referring to the drawings herewith, where- 30 in a preferred embodiment of the invention is disclosed, Fig. 1 is a central vertical section through an apparatus embodying my invention, the carbonating apparatus being shown in elevation; Fig. 2 is a horizontal section on the line 2—2 of Fig. 1; Fig. 3 is a broken side elevation of the refrigerating apparatus, 35 and Fig. 4 is a plan view of the rack supporting the inner tank of the refrigerating device. Like numerals of reference are applied to like parts in all the views.

In the construction of devices for dispens- 40 ing beverages for use in drug stores, and soft drink stands a great deal of difficulty has been experienced in arranging the refrigerating apparatus in such manner that it will be solid and compact and will allow 45 the packing of the inner ice container by means of saw dust or granulated cork and the like, and still allow the ready removal of the pipes connected with the refrigerating coil. In the drawings herewith, a construc- 50 tion is shown whereby this difficulty is over- come. In Fig. 1 I have illustrated a vertical section of the device, there being an outer container 1 which I prefer to construct in the form of a barrel of ordinary type, hav- 55 ing hoops 2 of brass or other ornamental material thereon and having a central metallic

tank 3 therein. This tank is cylindrical in form and is mounted on the bottom 4 of the barrel by means of a rack 5 supported upon the cross bars 6. The construction of the 60 rack 5 is shown best in Fig. 4. It is of skeleton form being made of transverse slats 7, secured to the cross members 6. This supports the cylindrical tank 3 in spaced relation from the bottom. The tank is also ma- 65 terially smaller than the barrel in which it is seated, which allows for the filling of the space below and at the sides of the tank with heat insulating material such as gran- 70 ulated cork, as shown at 8. The upper end 70 of the tank 3 is supported in spaced relation from the side by means of a ring 9 of wood or other similar material, which serves to close the space between the tank and the outer container, and at the same time to sup- 75 port the tank. A cover 10 is provided for the tank 3, this comprising a hollow com- 80 partment filled with heat insulating material 11, the upper edge of the metallic portion overlapping the supporting ring 9. A han- 85 dle of ordinary construction on the upper side of said cover serves to allow the manip- 90 ulation thereof.

The beverage which is to be dispensed by 95 means of this apparatus is kept in a contain- 85 er 12, preferably within a box or supporting table 13 upon which the barrel rests. The container 12 is connected by means of a pipe 13' with the container 14 for carbonating gas employed in soft drinks. The pressure 90 of the gas upon the beverage within the container 12 is sufficient to force said bever- 95 age through a vertical pipe 15 to the dis- 100 pensing and refrigerating tank previously described.

The beverage is preferably in sweetened 105 form, ready for use, and is run through a refrigerating coil 16 within the tank 3, said coil being kept at approximately freezing 110 temperature by means of ice 17 surrounding the said coil.

In the mounting of the inlet and outlet to and from the coil 16, I have provided an especially efficient and strong arrangement. I have on one side adjacent the said inlets, 105 two vertical supporting bars 19 and 20. These bars are fitted closely against the outer wall of the tank 3 and at their lower ends contact with the inner wall of the outer container 1. At their upper ends, which are 110 at a point spaced below the upper ends of the tank, they are held firmly against the

inner container 3 and supported in that position by means of blocks 20'. These two upright supporting members are provided with openings 21 to receive supporting pipes 22. The said pipes 22 extend through the uprights into contact with the wall of the tank 3. At their outer ends they are supported within a recess 23 in the inner wall of the barrel 1. The pipe 15 leading from the container for the beverage is connected by means of an elbow 24 to a pipe 25, which extends through the wall of the barrel and is supported within one of the pipes 21 and connects at its inner end with the inlet end of the coil by means of a coupling 26 of ordinary construction. The outlet end of the coil is also supported within one of the pipes 21 and connects at its outer end with the faucet or tap 28 by means of which the beverage may be drawn off. The small drain pipe 29 at the lower end of the refrigerating tank allows for the overflow of the water resulting from the melting ice.

The dispensing apparatus thus arranged is compact in form and attractive in appearance. It is especially strong, and may be operated in a particularly efficient manner. It sometimes becomes necessary to disconnect the pipes from the barrel and the tank therein for cleaning purposes. It is also found that the pipes may need renewing and repair, and in such case the parts may be disconnected and the coil removed so that repairs or replacements may be made, and the containing tank 3 properly cleaned. In such case, if the supporting pipes 21 were not provided, the granulated cork or saw dust or other insulating material would fill the passage through which the connecting pipes are passed, and thus interfere with the replacement thereof when repairs and cleaning operations were com-

pleted. This arrangement avoids such difficulty and maintains a rigid and firm support for the pipes connected with the coil. 45 The use of the upright supports 19 and 20 serve also to maintain the inner tank 3 in rigid upright position, and do not interfere with the use of the heat insulating material.

Having thus described my invention, what I claim as new and desire to protect by Letter Patent is:

1. In a beverage dispenser, an outer barrel-shaped container, an inner refrigerating tank, means spacing said tank from the wall of said container, heat insulating material in the space thus provided, upright supports along the wall of said tank, means to hold the upper ends of said supports in rigid position against said tank, pipes of rigid material supported at one end in said container and at the other end in said upright supports, a refrigerating coil of pipe in said tank, and fluid conducting pipes passing through said barrel, said rigid supporting pipes and connected with the ends of said coil in the manner described. 60

2. In a beverage dispenser, an outer container, a heat insulated inner tank, means to retain said tank in spaced relation inside said container, including two upright supporting bars, pipes of rigid material supported at their outer ends in said container and at their inner ends supported in said bars, a refrigerating coil in said tank, a pipe 75 adapted to connect a beverage container with said coil, said connecting pipe passing through one of said rigid pipes, and an outlet pipe supported in the other of said rigid pipes in the manner described. 80

In testimony whereof, I hereunto affix my signature this the 4th day of September, A. D. 1923.

ISAAC A. STEIN.
